UNITED STATES PATENT OFFICE

LEWIS RUTHERFURD STUYVESANT, OF ALLAMUCHY, NEW JERSEY

SAFETY DEVICE FOR FIREARMS

Application filed April 27, 1929. Serial No. 358,601.

The invention relates to safety devices for firearms.

The various types of automatic firearms now in use, while provided with certain safe-
5 guards to prevent accidental and uninten-
tional firing, have been found to be unsafe even to those familiar with such when carry-
ing, cleaning, or handling the firearm. Nat-
urally, to those unfamiliar with the use there-
10 of, the danger of accidental and uninten-
tional firing is tremendously increased.

The reason for this appears to be that the majority of safety devices now provided are so placed on the firearm as to render their 15 operation unnoticed or difficult of notice by those grasping the butt of the piece. Conse-
quently, it may happen that the firearm will be in operative position, and slight pressure on the trigger will cause firing. This is par-
20 ticularly true in the automatic revolvers, which have a safety device conforming to the shape of the butt at the extreme rear thereof, and which, when pressed, releases the trigger and firing mechanism from a locked position.

25 In some instances, additional safety means are provided in this type of firearm, such as a safety lever which is pivoted on the side of the frame adjacent the butt, and which slides into recesses in the breech-side when the lat-
30 ter is in closed or open position. Such safety locks, when manipulated, remain in either operative or inoperative position, as desired. When in inoperative or an open position, the opportunity for accidental and unintentional 35 firing becomes probable, for, by simply grasping the butt for firing, the primary safety device attached thereto also will be thrown out of operative locking position. Unless and until the breech-slide safety de-
40 vice is again pushed into locking position, the firearm is, of course, dangerous to handle and memory must be entirely relied upon to recall the necessity of manipulating the breech-
45 slide safety device, and observation of its po-
sition must be made to determine whether the firearm is safe.

With this situation clearly in mind, it is the object of this invention to provide a safety locking means which will be abso-
50 lutely fool-proof.

Another object of the invention is to pro-
vide a positive and automatic safety locking means.

Another object of the invention is to pro-
vide safety locking means which is normally 55 urged or moved toward its safety position, and requires, at all times, manipulation to disengage the device from operative position.

Another object of the invention is to pro-
vide a safety locking means which, after 60 each firing, whether one shot or the whole magazine is fired, will become operative for safety locking.

Another object of the invention is to pro-
vide a safety locking means which may be 65 applied to any firearm of the type described without changing or disturbing the mecha-
nism thereof.

Still another object of the invention is to provide a safety locking means which is sim-
70 ple in construction, not liable to breakage, and inexpensive to manufacture.

With these and other objects in mind, one embodiment of the invention is shown by the drawings, in which:

75 Figure 1 is a side view of a firearm show-
ing the invention,

Figure 2 is a top view of the firearm,

Figure 3 is a partial side view of the fire-
arm showing the inner construction of the in-
vention,

Figure 4 is a detail of the trigger and ham-
mer mechanism of one type of firearm to
which my invention may be applied.

Referring specifically to the drawings, in 85 which an automatic revolver of the Browning type is used, for example only, and which, in itself, forms no part of the present invention, except as in combination with the safety locking means, 1 indicates the frame having 90 the butt handle 2, barrel 3, trigger guard 4, and trigger 5. The breech-slide 6, of usual construction, is provided with recesses 7 and 8, to lock said breech-slide in recoiled and normal positions, respectively.

Attached to the frame of the firearm, ad-
jacent and slightly above the butt handle, is
the safety lever 9, which is pivoted at 10 on
a pin extending through the frame, and is
provided with a projection 11 adapted to 100

engage and interlock with the recesses 7 and 8 in the breech-slide 6, and a thumb rest 12 shaped to comfortably conform to the thumb.

Directly below the safety lever 9, and attached in any convenient manner to the side of the butt handle, is a pressure exerting means 13, comprising, in the particular instance shown in the drawings, a cylindrical member 14 having a flat member 15 integral therewith, provided with screw holes and screws therein for attaching to the firearm. The cylindrical member 14 contains a spring 16 abutting the bottom, which presses against the plunger or spring bolt 17 which, it will be observed, is rounded at its upper end 18 to give frictionless contact. The pressure exerting means 13 may be mounted in any suitable manner, and, as here shown, is sunk into a properly sized space cut in the wooden side pieces 19 of the butt handle, and when correctly placed does not appreciably protrude beyond said wooden side pieces, and, therefore, in no way interferes with the grasping of the butt handle.

The rod 17 is always in contact with, and exerts constant pressure against, the locking lever 9 to urge the latter member always toward the breech-slide and into engagement with the recesses therein. The pressure of the spring, however, must not be so great as to cause undue effort on the part of the person using the piece, otherwise such effort would tend to impair the accuracy of aiming.

Protruding slightly from the back of the butt handle is the usual grip lever 20, which operates when compressed to release the trigger from a locked position and forms the primary safety means of this particular type of firearm.

The trigger and hammer mechanism, as shown in Figure 4, is of the usual type, and is illustrated merely to show the relation between such mechanism and the safety device of my invention with this type of firearm. The grip lever 20; the sear 21, and the hammer 22 are all of usual construction and operate in the usual manner, the sear having a stud 23 which is adapted to engage a stud 24 carried by the lever 9 and operating through a suitable slot or segmental opening in the frame, so that, as the manual safety lever 9 is manipulated, the stud 24 will perform its usual interlocking and releasing functions for the firing mechanism. This mechanism being old and well known, further description of it and its operation is not deemed necessary, but for a full understanding of my invention, it is illustrated in its conventional form and described.

Experts in the firing of revolvers recommend, in order to obtain maximum marksmanship, that the thumb be held parallel to and against the barrel. With the invention here disclosed, it is required that the thumb be in this position in order to release, and hold

in release, the safety locking lever, and this, therefore, aids in correctly presenting the firearm for firing.

The thumb piece is so shaped as to make an extremely comfortable rest, and by simply applying downward pressure thereto, when the butt handle has been grasped and the trigger grip lever released, the revolver is ready for firing.

After firing, if the pressure is released on the thumb piece of my automatic safety lock, the breech-slide will immediately become securely locked, so that no matter if any other safety device provided becomes inoperative, the gun cannot possibly be fired, thereby eliminating the probability of accidental and unintentional discharge.

It is understood that the invention comprising the automatic and positive safety locking means not only may form an attachment to firearms of the type described, but also may be a part of the original mechanism and be constructed as shown in the drawings.

It is also particularly understood that the automatic and positive safety locking means can be placed in other relations than that here shown to illustrate the invention, and perform the function for which it is intended.

I claim:

1. In a firearm, the combination of a frame, a barrel, a movable breech-slide, a safety device to hold said slide in a predetermined position, and means tending always to hold said device positively in engagement with said slide.

2. In a firearm, the combination of a frame, a barrel, a movable breech-slide, a safety device to hold said slide in any one of a plurality of predetermined positions, and means tending always to hold said device positively in engagement with said slide.

3. In a firearm, the combination of a frame, a barrel, a movable breech-slide, a safety device to hold said slide in a predetermined position, and automatic means tending always to hold said device positively in engagement with said slide.

4. In a firearm, the combination of a frame, a barrel, a movable breech-slide, a safety device to hold said slide in a predetermined position, and resilient means tending always to hold said device positively in engagement with said slide.

5. In a firearm, the combination of a frame, a barrel, a movable breech-slide, a safety device to hold said slide in a predetermined position, and a spring bolt tending always to hold said device always in position to positively engage said slide.

6. In a firearm, the combination of a frame, a barrel, a movable breech-slide, a manually operable lever to hold said slide in a predetermined position, and means tending always to

- hold said lever positively in engagement with said slide.
7. In a firearm, the combination of a frame, a barrel, a movable breech-slide, and a spring-impelled lever tending always to positively engage and hold said slide in a predetermined position.
8. In a firearm, the combination of a frame, a barrel, a breech-slide movable to a plurality of different positions, and a spring-impelled lever tending always to positively engage and hold said slide in at least one of its different positions.
9. In a firearm, the combination of a frame, a barrel, a breech-slide movable to a plurality of different positions, and a spring-impelled lever tending always to positively engage and hold said slide in any one of its different positions.
10. In a firearm, the combination of a frame, a barrel, a breech-slide movable to a plurality of different positions, firing means, safety mechanism to hold said slide and firing means against movement when each is in a predetermined position, and means tending to move said safety mechanism always into engagement with said slide and firing means.
11. In a firearm, the combination of a frame, a barrel, a movable breech-slide, firing means, a manually-operable safety lever to engage said slide and hold it in predetermined position, means operable on movement of said lever to lock said firing means, and means tending to move said lever and said lock always into safety position.
12. In a firearm, the combination of a frame, a barrel, a movable breech-slide, firing means, a manually-operable safety lever to engage said slide and hold it in predetermined position, a locking device for said firing means on said lever, and spring means engaging said lever and tending to move said lever and locking device always into safety position.
13. An attachment for a firearm having a breech-slide and a safety lever to engage and hold said slide in a predetermined position, comprising a spring member in engagement with said lever and tending always to positively move said lever into safety engagement with said slide.
14. An attachment for a firearm having a breech-slide and a safety lever to engage and hold said slide in a predetermined position, comprising a spring-projected bolt engaging and tending always to positively move said lever into safety engagement with said slide.
15. An attachment for a firearm having a breech-slide and a safety lever to engage and hold said slide in a predetermined position, comprising a bolt-housing adjacent said lever, and a spring-projected bolt in said housing engaging and tending always to positively move said lever into safety engagement with said slide.
16. An attachment for a firearm having a breech-slide and a safety lever to engage and hold said slide in a predetermined position, comprising a removable bolt-housing attached to the firearm adjacent said lever, and a spring-projected bolt in said housing engaging and tending always to positively move said lever into safety engagement with said slide.
17. An attachment for a firearm having a breech-slide and a safety lever to engage and hold said slide in a predetermined position, comprising a bolt-housing, a spring projected bolt in said housing engaging and tending always to positively move said lever into safety engagement with said slide, and means carried by said bolt-housing for detachably securing the attachment to the firearm.
18. An attachment for a firearm having a breech-slide and a safety lever to engage and hold said slide in a predetermined position, comprising a bolt-housing, a spring projected bolt in said housing engaging and tending always to positively move said lever into safety engagement with said slide, and means integral with said housing for detachably securing the attachment to the firearm.
19. An attachment for a firearm having a breech-slide and a safety lever to engage and hold said slide in a predetermined position, comprising a removable bolt-housing having an integral rib thereon and adapted to be seated in a recess in the butt of the firearm in substantial conformity with the contour thereof, and a spring projected bolt in said housing engaging and tending to move said lever always into safety engagement with said slide.
20. In a firearm, the combination of a frame, a barrel, a breech-slide, a butt having a recess therein, a safety lever to engage and hold said slide in predetermined position, a removable bolt-housing secured in the recess of the butt, and a spring projected bolt in said housing engaging and tending to move said lever always into safety engagement with said slide.
- In testimony whereof I have hereunto set my hand.
